UNITED STATES PATENT OFFICE.

EVERETT ROBERT JONES, OF MILAN, KANSAS.

COMBINATION-TOOL.

SPECIFICATION forming part of Letters Patent No. 638,871, dated December 12, 1899.

Application filed June 22, 1899. Serial No. 721,477. (No model.)

To all whom it may concern:

Be it known that I, EVERETT ROBERT JONES, a citizen of the United States, residing at Milan, in the county of Sumner and State of Kansas, have invented a new and useful Combination-Tool, of which the following is a specification.

The invention relates to improvements in combination-tools.

10 The object of the present invention is to improve the construction of combination-tools and to provide a simple, inexpensive, and efficient device adapted to be readily arranged to form a pipe or nut wrench and capable of 15 operating as a bolt-holder to engage the head of a bolt to prevent the same from turning while the nut is being screwed on or off.

The invention consists in the construction and novel combination and arrangement of 20 parts hereinafter fully described, illustrated in the accompanying drawings, and pointed out in the claims hereto appended.

In the drawings, Figure 1 is a side elevation of a combination-tool constructed in accordance with this invention and arranged to form a wrench. Fig. 2 is a similar view showing the device arranged to form a bolt-holder. Figs. 3 and 4 are detail views of the slide. Fig. 5 is a detail view of the movable jaw. Fig. 6 30 is a detail view of the claw which forms the stationary jaw.

Like numerals of reference designate corresponding parts in all the figures of the drawings.

35 1 designates a bar provided at one end with a claw 2, arranged at an angle, provided with teeth, and adapted to form a stationary jaw and coöperate with an adjustable jaw 3 to form either a pipe or nut wrench. The jaw

40 3 is angularly bent and provided at its inner edge with teeth shouldered at their inner ends, and the fixed jaw 2 is adapted to be partially rotated, as illustrated in Fig. 1, to extend it toward or from the adjustable jaw to arrange

45 it approximately parallel with the outer portion of the same at an angle thereto. The outer portion of the adjustable jaw is provided with a slight bend, and when the fixed jaw is arranged as shown in dotted lines in Fig. 1 it

50 is substantially parallel with the outer portion of the adjustable jaw, and the parts are then adapted to form a nut-wrench. When

the parts are arranged as shown in full lines in Fig. 1 of the drawings, the jaws are disposed at an angle and the teeth are adapted to engage a rod, pipe, or other round surface.

The adjustable jaw 3, which may be split, as shown, is provided with a straight shank 4, having an eye 5 adapted to engage a hook 6 of a slide 7, and the latter is mounted on the bar 1. The eye 5 of the shank of the hook is also linked into one end of a chain 8, adapted to engage the hook of the slide for a purpose hereinafter described.

The slide 7, which is provided with a round bore or opening 9, is arranged on the bar 1 and is composed of sections 10 and 11, hinged together at one side of the opening 9 and provided at the opposite side with perforated ears 12, receiving a bolt or screw 13, and the latter, which is provided at one end with a head, has its threads engaged by a clamping-nut 14, adapted to permit the nut to be readily turned, whereby the slide may be clamped on the rod at any desired adjustment. The section 11, 75 which carries the hook 6, is provided with a longitudinal groove 16, contracted at the inner side and forming an eye to receive a rounded rib 18 of the section 10. The connection thus formed between the sections provides sufficient hinge movement to enable the slide to clamp and release the rod or bar 1. The rib 18, which is interlocked with the section 11, is introduced into the groove at one end thereof, and the parts may be readily disengaged from each other when the bolt or screw 13 is removed.

When the parts are arranged as illustrated in Fig. 2 of the accompanying drawings, the device is adapted to be used as a bolt-holder 90 to prevent a bolt from turning while its nut is being screwed on or off. The stationary jaw or claw is engaged with the head of the bolt, as shown in Fig. 2, and the chain is connected with the hook to permit the movable jaw to be readily interlocked with any fixed object, and as any one of the links of the chain may be arranged on the hook it is an easy matter to engage the movable jaw to anchor the device. This will enable the lever 100 to exert sufficient pressure upon the head of the bolt or screw to prevent it from rotating.

The invention has the following advantages: The combination-tool, which is simple

and comparatively inexpensive in construction, is strong and durable, and it is adapted to be easily arranged for engaging either a round or rectangular object, and it forms an efficient pipe and nut wrench. It is only necessary to rotate the rod or bar 1 one-half a revolution to change the device and convert it into a nut or pipe wrench, and it is readily adjustable to enable it to engage the object to be operated on. The device is also adapted for use as a bolt-holder, and it is capable of engaging the head of a bolt or screw with sufficient pressure to prevent it from turning while its nut is being screwed on or off.

15 Changes in the form, proportion, size, and the minor details of construction within the scope of the appended claims may be resorted to without departing from the spirit or sacrificing any of the advantages of this invention.

20 What is claimed is—

1. A device of the class described comprising a bar provided with a fixed or stationary jaw arranged at an angle, a slide mounted on the bar, and an adjustable jaw connected 25 with the slide and having an outer engaging portion arranged to coöperate with the fixed or stationary jaw, said bar being adapted to be rotated to extend the fixed or stationary jaw inward or outward to arrange it approximately parallel with the outer portion of the adjustable jaw, at an angle thereto, to form either a pipe or nut wrench, substantially as described.

2. A device of the class described comprising a bar having a stationary jaw arranged at 35 an angle, an adjustable jaw having an angularly-bent engaging portion disposed opposite the stationary jaw, and a slide connecting the adjustable jaw with the bar, the latter being adapted to be rotated to extend the stationary jaw inward or outward to arrange the stationary jaw approximately parallel with the outer portion of the adjustable jaw and at an

angle thereto, to form either a pipe or a nut wrench, substantially as described.

3. A device of the class described comprising a bar having a fixed or stationary jaw arranged at an angle, an adjusting-jaw provided with a shank and having an angularly-bent outer engaging portion arranged opposite the stationary or fixed jaw, the latter being adapted to be rotated to arrange it at an angle to the adjustable jaw and also approximately parallel with the outer portion of the same and a slide adjustably mounted on the bar and provided with a hook detachably engaging the shank of the adjustable jaw, substantially as described.

4. A device of the class described comprising a slide having a hook, an adjustable jaw 60 provided with an eye and having a chain, said eye and chain being adapted to engage the hook, and a bar having a stationary jaw and arranged in the slide, said bar being adapted to be rotated to arrange the stationary jaw 65 approximately parallel with the outer portion of the adjustable jaw and at an angle thereto, substantially as described.

5. A device of the class described comprising a bar having a fixed jaw, a slide composed 70 of two sections, one of the sections being provided with a longitudinal groove and the other section having a longitudinal rib arranged in the groove and having a limited movement to form a hinge-joint, means for adjustably 75 connecting the sections, and an adjustable jaw carried by the slide, substantially as described.

In testimony that I claim the foregoing as my own I have hereto affixed my signature in 80 the presence of two witnesses.

EVERETT ROBERT JONES.
